(57) **CLAIM**

The ornamental design for a combined fuel filter and fuel pressure regulator as shown and described.

DESCRIPTION

FIG. 1 is a front, top perspective view of a combined fuel filter and fuel pressure regulator according to the present invention;

FIG. 2 is a rear, bottom perspective view thereof;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof; and,

FIG. 8 is a bottom plan view thereof.

The broken lines in FIGS. 1-8 are for the purpose of illustrating portions of the combined fuel filter and fuel pressure regulator that form no part of the claimed design.
